To all whom it may concern:

Be it known that I, Morris Spector, a citizen of the United States of America, residing in city of New York, county of New York, and State of New York, have invented a new, original, and ornamental Design for a Cape, of which the following is a specification, reference being had to the accompanying drawing, forming part thereof.

Fig. 1 is a front view of a cape showing my new design.

The characteristic feature of my design resides in the combination on the cape as shown of the shirred yoke of the instant shape, said yoke being relatively shallow in the front and comparatively deep in the back.

I claim:

The ornamental design for a cape substantially as shown and described.

MORRIS SPECTOR.
